DESIGN FOR A MULTIPLE FUNNEL

Max A. Stone, Brooklyn, N. Y.

Application January 31, 1946, Serial No. 126,119

Term of patent 14 years

(Cl. D44—29)

To all whom it may concern:

Be it known that I, Max A. Stone, a citizen of the United States, residing at Brooklyn, in the county of Kings, in the State of New York, have invented a new, original, and ornamental Design for a Multiple Funnel, of which the following is a specification, reference being had to the accompanying drawing, forming a part thereof.

Fig. 1 is a side elevational view of a multiple funnel, showing my design; Fig. 2 is a bottom plan view of the same; Fig. 3 is a top plan view of the same, and Fig. 4 is a sectional view taken on the line 4—4 of Fig. 3.

I claim:

The ornamental design for a multiple funnel, as shown.

MAX A. STONE.
